UNITED STATES PATENT OFFICE.

ROBERT J. BARKLEY, OF CHANUTE, KANSAS.

DESIGN FOR A CARTON-BLANK.

SPECIFICATION forming part of Design No. 29,094, dated July 26, 1898.

Application filed July 2, 1898. Serial No. 685,056. Term of patent 14 years.

To all whom it may concern:

Be it known that I, ROBERT J. BARKLEY, of Chanute, in the county of Neosho and State of Kansas, have invented and produced a new and original Design for a Carton-Blank, of which the following is a full, clear, and exact description.

Reference is to be had to the accompanying drawing, which represents a plan view of a carton-blank embodying my design.

The design consists in the following-described features: a panel *a*, at each end of which is a rectangular extension *b* and on each side of which are two flanking panels, such panels being, respectively, designated *c* and *d* and *e* and *f*. The panels *d* and *e*, being those directly contiguous to the central panel *a*, have at each end extensions *e'* and *d'* projecting beyond the extensions *b* and having the edges adjacent to the extensions

b curved away from said extensions. The panel *f* has slits *g*, presenting an angular appearance, and the panel *c* has a centerpiece *h*, the center of which is curved inwardly and merged into the rounded ends of the centerpiece, such rounded ends forming reentrant angles *i* with the curved upper edges *j* of the ends *c'* of the panel *c*, the outer edge of which has a compound curve. Further, the end extensions *e'* and *d'* have transverse slits *e²* *d²*, 25 the slits *d²* running from the curved edge of the extensions *d'*, while the slits *e²* run inward from the straight edges of the extensions *e'*. 30

I claim—

The design for a carton-blank, substantially as herein shown and described.

ROBERT J. BARKLEY.
